GOLFER'S MULTI-PURPOSE TOOL

Thomas H. McKelvey, 5195 Rivoli Drive,
Macon, Ga. 31204

Filed Jan. 8, 1973, Ser. No. 321,988

Term of patent 14 years

Int. Cl. D21—02
U.S. Cl. D34—5 CB

FIG. 1

FIG. 2

FIG. 3

FIG. 4

FIG. 5

FIG. 6

FIG. 7

FIG. 1 is a perspective view of the tool with the divot pick thereof extended to its position of use;

FIG. 2 is a plan elevational view of the tool with the divot pick thereof retracted to its housed position;

FIG. 3 is a plan elevation of the tool, viewed from the opposite side as compared to FIG. 2;

FIG. 4 is an end elevational view, taken from the divot pick end of the tool;

FIG. 5 is an end elevational view taken from the opposite end of the tool;

FIG. 6 is a side elevation of the tool, the view from the opposite side being complementary; and

FIG. 7 is a perspective view of the tool with the combined screwdriver and file thereof extended for use.

I claim:

The ornamental design for a golfer's multi-purpose tool, as shown and described.
